UNITED STATES PATENT OFFICE

2,554,829

SPRAY DEVICE

Sten Anders Wilhelm Jeurling, Stockholm, Sweden, assignor to Super-Spray Paint Corporation, Kings County, N. Y., a corporation of New York

Application November 24, 1948, Serial No. 61,877
In Sweden December 1, 1947

7 Claims. (Cl. 91—45)

1

This invention relates to spray devices for liquified material, such as paint, and more particularly to such devices having a nozzle unit for the material to be sprayed and gaseous spray pressure medium for spraying said material and laterally of the axis of said nozzle a gas burner having orifices for ejecting gas to form flames substantially in the same direction as that of the sprayed material so as more or less completely to surround the jet of sprayed material. Due to the considerable speed of the sprayed jet of the liquified material there is a tendency of establishing a vacuum round the jet and in consequence thereof the flames will decline towards said jet and may converge too much and even burn the jet.

The primary object of the invention is therefore to eliminate the vacuum between the jet of liquified material and the flames and a second object is to provide means for performing such eliminating without unduly cooling the liquified material or the thing to be sprayed. A further object is to provide means for controlling the degree of elimination of the vacuum, at least partially for the purpose of influencing the direction of the flames. It is also an object of the invention so to design the spray device as to prevent the combustible burner gases from being intermingled with the spray pressure medium or any other gases in channels of the device containing oxygen. A still further object is to provide a sprayer having a readily removable or exchangeable burner so as to enable one and the same spray gun to be used for different purposes.

To obtain these objects and other advantages that will be evident from the following description at least one conduit is provided to connect the space between the nozzle unit for the liquified material and the orifices of the burner with the surrounding atmosphere or with a source of pressure gas, at least in the latter case means being provided for heating said pressure gas.

The invention will now be described more in detail with reference to the accompanying drawing, but it is to be understood that the invention shall not be limited to the embodiments thus described or shown.

In the drawing—

The figure is a schematic side view partially in section, of a nozzle head in accordance with my present invention.

Being particularly applicable to the hot spraying of heated paint, the invention will now be described with reference to that kind of liqui-

fied material, although it may be used with advantage also for other materials.

In a metallic block or body 1 a central bore or recess 4 is provided to give room for the nozzle unit which will be described presently. At some distance laterally of said bore or recess is another recess 2 and between this recess and the bore 4 there is a further recess 3. A tube 17 for heated paint is attached to the rear side of the bore 4 and a flanged nozzle body 5 is partly inserted into the inner end of the tube 17, the flange 7 of said nozzle body being seated on corresponding shoulder in the bore 4. The body 5 has a central paint chamber 6 having a front orifice 15 in an extended portion of body 5. The various recesses 2, 3 and 4 are closed at the front side by a cover 9 secured to the body 1 by means of threads 11, so as to form from said recesses a burner gas chamber 2, a protection gas chamber 3 and a spray gas chamber 8. This cover 9 is provided with a series of orifices 12 along the burner chamber 2 and orifices 13 along the protection gas chamber 3. Around the extended portion 15 of the nozzle body 5 there is a hole 14 in the cover 9 of such a width that an annular orifice 16 will be formed about said extended portion so as to form an outlet for the chamber 8.

The various gas chambers 2, 3 and 8 are connected to corresponding supply conduits 18, 19 and 20, respectively, for supplying burner gas or air-gas mixture, protection gas and spray pressure gas, respectively. A heating member is provided at least in the protection gas conduit 19 as indicated by the electrical resistance 10, but preferably also in the pressure medium conduit 20 as indicated by 10'. It is to be understood that the invention is by no means restricted to electrical heating means but may as well make use of any practical heating means, such as a steam jacket or a gas burner. The heating member may preferably be arranged in or about the source of protecting gas or spray gas, respectively.

45 All the conduits 17—20 leading to the nozzle head but in particular the protection gas conduit 19 may be provided with a control valve 21, 21'.

The nozzle unit 5, 14—16 may have any suitable form for providing a paint jet of any desired shape. Thus circular orifices 15 and 16 will form a circular jet and adequate means, well known to those skilled in the art, will render a more or less flattened jet. The chambers 55 2 and 3 are preferably shaped so as to corre-

spond to the shape of the paint jet. The distances between, on the one hand, the orifices 12 and 13 and, on the other hand, the paint jet will in such case be substantially equal. In case of a circular jet the chambers 2 and 3 are preferably annular and the corresponding recesses are then easily turned in the nozzle block 1. For flattened jets the chambers 2 and 3 may be more or less rectilinear.

In operating this device compressed air is admitted through the conduit 20 to chamber 8 and a jet of air will be ejected through the orifice 16. Burner gas, which may be an appropriate mixture of combustible gas and air, is simultaneously admitted to chamber 2 through conduit 18 and the gas is ignited at the orifices 12. Protection gas is supplied through conduit 19 to chamber 3 and the valve 21 is regulated until the desired direction of the flames from the orifices 12 will be obtained. The heating member 10 and, if desired, the heating member 10' are regulated according to the prevailing conditions. By suitable setting of the valves 21 and 21' and appropriate supply of burner gas through conduit 18 just so great a portion as desired of the surface of the object to be painted will be covered by the flames from the burner 2. When the correct adjustment of the supply of the various gases has been attained, the heated paint will be admitted through conduit 17 to the paint chamber 6 and the paint will then be ejected by the sucking influence of the pressure air forced out through the orifice 16.

The means for supplying paint and burner gas and the various containers for paint, burner gas and pressure gas being commonly known to those skilled in the art, such means will not be described here.

Having now particularly described and ascertained the nature of my said invention and in what manner the same is to be performed I declare that what I claim is:

1. A spray device having a nozzle unit for liquified material to be sprayed and for gaseous spray pressure medium for spraying said mate-

rial, laterally of the axis of said nozzle a gas burner having orifices for ejecting flames substantially in the direction of the axis of said nozzle, a source of protection gas, at least one conduit connecting the space between said nozzle and said orifices with said source, and means for heating said protection gas.

2. A spray device as claimed in claim 1, characterized in means in said conduit for controlling the flow of gas therein.

3. A spray device as claimed in claim 1, characterized in means for heating said spray pressure medium.

4. A spray device, comprising a block, in said block at the centre a spray material chamber and a spray medium chamber, laterally of said chambers a protection gas chamber and further laterally of the last named chamber a burner gas chamber, all said chambers having supply conduits and forwardly directed exit orifices, at least the supply conduit of said protection gas chamber being provided with gas heating means.

5. A spray device as claimed in claim 4, comprising in at least the supply conduit of said protection gas chamber a control valve.

6. A spray device as claimed in claim 1, in which the orifices of said gas burner are situated substantially at the same distance from the jet of liquified material ejected from the nozzle.

7. A spray device as claimed in claim 1, comprising a nozzle head and in said head a distribution chamber for combustible gas and a distribution chamber for pressure medium, a continual impervious wall being arranged between said chambers.

STEN ANDERS WILHELM JEURLING.
